UNITED STATES PATENT OFFICE.

LEWIS F. BETTS, OF NEW YORK, N. Y.

GAS-BURNING HEATER.

SPECIFICATION forming part of Letters Patent No. 744,283, dated November 17, 1903.

Application filed July 17, 1903. Serial No. 165,899. (No model.)

To all whom it may concern:

Be it known that I, LEWIS F. BETTS, a citizen of the United States, residing in the city of New York, borough of Brooklyn, in the 5 county of Kings and State of New York, have invented a certain new and useful Improvement in Gas-Burning Heaters, of which the following is a specification.

The invention relates to heaters arranged 10 to serve with the usual illuminating-jet outlets in the gas-supply pipes; and the object of the invention is to provide an apparatus which shall have great radiating-surface and a burner therefor which will produce the required heat and also afford brilliant illumination and which shall be easily and cheaply 15 manufactured and be neat and attractive in appearance.

The invention consists in certain novel arrangements of parts and details of construction by which the above objects are attained, to be hereinafter described.

The accompanying drawings form a part 20 of this specification and show a preferred 25 form of the invention.

Figure 1 is a side elevation of the heater. Fig. 2 is a corresponding diametrical section. Fig. 3 is a view of the under face of the radiator portion, and Fig. 4 is a plan or top 30 view of the burner portion. Fig. 5 is a vertical section showing a portion of Fig. 2 on a larger scale. Fig. 6 is a similar view of another portion of the same figure.

Similar letters of reference indicate the 35 same parts in all the figures.

Gas from the service-pipe (not shown) is received by the nipple A, adapted to be screwed upon an ordinary illuminating-jet outlet, and, passing through a tube or cone A' 40 of wire-gauze or other desired equalizing distributor fills the interior of the gas-chamber A², secured to the nipple A. The gas-chamber may be of any desired form. I have shown it as having a dome-shaped upper portion having a central exteriorly-screw-threaded boss A³ and an annular shoulder A⁴, below which is a horizontal annular rim or deck A⁵, in which is a series of equally-spaced small holes a a, through which gas from the 45 interior of the chamber issues and is burned in a series of vertical jets. The lower por-

tion of the chamber curves inwardly and downwardly and terminates in an upwardly-extending tube A⁶ within the chamber, screw-threaded to match to the nipple A.

It is important in attaining the best heating results that there be as many jets as practicable, and it is also important in effecting the desired complete combustion that each jet maintains its individuality and does not 55 mingle with the next in the series. These essential features are secured by properly spacing the jet-holes, and the free combustion desired is further insured by the employment of a cap B, applied on the upper portion of 60 the gas-chamber and having a hole matching to the boss A³, serving to hold the cap concentrically thereon. The cap has an annular flange B' at the level of the shoulder A⁴, extending beyond the deck A⁵ and having an 65 annular skirt or depending lip B², reaching a little below the level of the deck and encircling the latter with a slight air-space between. The flange B' is pierced with a series 70 of openings b, one for each jet-hole a and exactly concentric thereto, the desired position being determined and insured by matching an aperture b' in the flange with a swell or boss A⁷, produced in the deck for the purpose. Each jet is thus supplied with the required 75 volume of air delivered uniformly around the jet, and when the parts have become heated the air thus supplied is warm and in the best condition to insure perfect combustion and produce an extremely brilliant white flame. 80 I prefer to produce the holes a by punching in suitable dies, for the reason that greater uniformity may be thus attained than by drilling, and by making all the jet-holes of exactly the same diameter and supplying the 85 same amount of air to each jet all burn uniformly and attain a uniform height or length of jet.

Upon the boss A³ is screwed the lower end 90 of a short tube or standard C, locking the cap B beneath it and having a bead or narrow flange C', upon which rests an inverted bell C², serving as a flame-spreader and preventing the jets from curving inwardly and mingling at their upper ends. Screwed into the 95 upper end of the standard C is a short nipple D', formed on an inverted cap D, attached to

and forming part of the hood or radiator E, thus supported above the jets and receiving heat therefrom.

The radiator is circular and of considerably larger diameter than the cap B and is, in effect, a hollow shell of sheet metal comprising two main portions spun to the forms shown in the drawings, one, the top E', being flat on the upper face, excepting as stiffened by the 10 annular interior beads e' e² formed therein, the latter, e², serving also to hold the inverted cap D' by being forced over and locked beneath the flange D² thereon. The top E' has a slightly-flared depending flange E², secured 15 by a lapped joint to an oppositely-flared flange E³ on a second portion of the radiator, serving as a reflector. This portion comprises an inwardly and upwardly extending truncated cone E⁴, open at the upper end and 20 formed in one with the flange E³. The under face of the cone serves as a reflector for the heat and light from the jets below and may be whitened or otherwise treated to produce the desired reflecting-surface. I prefer to 25 use for this purpose a sheet of white asbestos paper M, cut to match the under face of the cone and having its lower edge received in a trough-like fold E⁵ of the metal at the junction of the cone and flange E³, the upper edge, 30 lying within a downward fold E⁶ at the upper margin of the cone, equipped with short lugs E⁷, adapted to be bent downwardly to hold the asbestos in place.

The opening at the top of the cone is large 35 enough to allow the upper ends of the jets to enter instead of striking directly upon the reflector, and the cone reaches nearly to the under face of the top E', leaving a narrow annular space sufficient for a slight circulation of air within the radiator, the holes e⁴ permitting the slow escape of products of 40 combustion and preventing the collection of dead air.

It will be noted that nearly all the parts 45 are of sheet metal spun or shaped in suitable dies to the desired forms and that soldered and riveted joints are avoided, thus permitting the heater to be cheaply manufactured, and by joining the burner to the radiator by 50 the threaded standard C the parts may be packed in the knocked-down condition in small compass for shipment and be easily set up for use.

The heater presents a large area of radiating-surface exposed directly to the circle of jets, and the arrangement of the latter with the air and gas-supply thereto insures brilliant illumination, aided by the effect of the reflector, and the whole forms an efficient 55 heater combined with an illuminating-burner adapted to serve on a drop-light stand, bracket, or chandelier.

Modifications may be made in the forms and proportions within wide limits without departing from the invention.

Other material may be substituted for the

asbestos as a reflecting-surface, or the under face of the cone may be enameled or otherwise coated to produce the desired effect.

I claim—

1. In a gas-burning heater, a gas-chamber having an annularly-arranged series of jet-holes equally spaced apart and separated to insure independent burning-jets, a cap over said holes and having coincident larger openings, a flame-spreader above and separated from said gas-chamber, and a radiator supported above the flame-spreader. 75

2. In a gas-burning heater, a gas-chamber having an annularly-arranged series of jet-holes, a cap over said holes and having coincident larger openings, a flame-spreader above said gas-chamber, a radiator above the flame-spreader, and an axially-disposed support common to said gas-chamber, flame-spreader 80 and radiator. 85

3. In a gas-burning heater, a gas-chamber having an annularly-arranged series of jet-holes, means above and in proximity thereto having openings larger than and coincident 90 with the openings of the said chamber and provided with a flange for insuring free combustion, a flame-spreader above and removed from said chamber and means, and a radiator supported above the flame-spreader. 95

4. In a gas-burning heater, a gas-chamber having an annularly-arranged series of jet-holes, a flanged cap above said holes and having coincident openings, a flame-spreader above said flanged cap, and a radiator supported above the flame-spreader. 100

5. In a gas-burning heater, a gas-chamber having an annular deck with a series of equally-spaced jet-holes therein, separated to insure independently-burning jets, an annular flange above said deck having a series of openings each concentric to one of said jet-holes, and an annular depending skirt encircling said deck, and a radiator above said cap adapted to be heated by the flames from 110 said jet-holes.

6. In a gas-burning heater, a gas-chamber having an annular deck with a series of equally-spaced jet-holes therein, separated to insure independently-burning jets, an annular flange above said deck having a series of openings each concentric to one of said jet-holes, and an annular depending skirt encircling said deck, a radiator above said cap adapted to be heated by the flames from 115 said jet-holes, and a flame-spreader between said cap and radiator. 120

7. In a gas-burning heater, a gas-chamber having an annularly-arranged series of jet-holes, a flanged cap above and in proximity to said gas-chamber and having a series of coincident larger openings, a flame-spreader above and removed from said gas-chamber, a radiator above the flame-spreader, and a coaxial support for all of said parts. 125

8. In a gas-burning heater, a gas-chamber having a series of annularly-arranged jet-

- holes, a radiator, a flanged cap over the holes of the gas-chamber and having coincident larger openings, and a coaxial separable support therefor.
- 5 9. In a gas-burning heater, a gas-chamber having an inlet-nipple and an annular deck provided with a series of equally-spaced jet-holes, a centrally-located boss on the top of said chamber, a cap having an aperture matching to said boss and an annular flange above said deck, provided with a series of openings each concentric to one of said jet-holes, an annular depending skirt on said flange encircling said deck, a standard 10 screwed upon said boss and holding said cap, a flame-spreader on said standard above said cap, and a radiator having an inwardly-coned lower face serving as a reflector, supported by said standard above said spreader.
- 15 10. In a gas-burning heater, a gas-chamber having a series of jet-holes, a cap over said holes and having coincident larger openings,
11. In a gas-burning heater, a radiator, comprising a hollow shell with closed top, an inwardly and upwardly extending truncated cone depending from said shell with an annular air-space beneath said top and between 20 the same and the cone, and means for allowing of the escape from said air-space above the bottom of the cone, of the products of combustion, combined with a gas-chamber having an annular series of jet-holes and a 25 cap over said holes and having coincident larger openings.
- 20

In testimony that I claim the invention above set forth I affix my signature in presence of two witnesses.

LEWIS F. BETTS.
